UNITED STATES PATENT OFFICE

HARRY W. HICKS, OF BROOKLINE, MASSACHUSETTS

TOOTHBRUSH

Application filed April 3, 1931. Serial No. 527,377.

This invention relates to a tooth brush particularly adapted for the thorough and proper cleansing of the teeth and massaging the gums adjacent to the exposed portions of the teeth. Although the brushing of teeth has been practiced for a long time, few of those who brush their teeth regularly brush them thoroughly, the inner surfaces of the teeth being especially neglected.

10 It is an object of the present invention to provide a brush by which all the exposed surfaces of each tooth may be simultaneously brushed, together with a gentle massaging of the adjacent marginal portions of the gums. 15 According to the invention a tooth brush is provided, the bristles of which are varied in length to form a central longitudinal channel extending from one end of the brush to the other, this channel being of a suitable size to 20 receive a row of teeth of ordinary size, the channel being sufficiently deep to permit the bristles defining the outer edge thereof to extend beyond the exposed portions of the teeth so as to come into contact with the gum 25 surfaces adjacent to the teeth. In order to accommodate the brush readily to the curved portions of the jaws, I may round off the longitudinal contour of the brush so that the bristles of maximum length occur at or near 30 the middle of the brush, the bristles at either end of the brush being considerably shorter. By this arrangement of bristles, a tooth brush embodying the invention will receive and embrace the teeth on any portion of either jaw. 35 Since the brush naturally guides itself into proper position for brushing the surfaces of the teeth and massaging the gums, the user naturally employs the brush in the correct way so that the teeth are properly cleaned 40 and the gums are properly and gently massaged.

Thus incorrect cleansing of the teeth, often resulting from laziness or ignorance of the correct use of an ordinary brush, is avoided 45 by the use of a brush embodying the present invention. If my improved brush is used at all, its structure almost compels its proper and correct use, so that a complete treatment 50 of the tooth surfaces and adjacent gum tissue is inevitably obtained unless a deliberate

effort is made to use the brush in some manner other than that which is naturally followed, as hereinafter described.

On the drawing,

Figure 1 is a perspective view of a tooth brush embodying the invention.

Figure 2 is a side elevation of the brush on a larger scale.

Figure 3 is a section on the line 3—3 of Figure 2.

The tooth brush illustrated on the drawing may comprise the usual elongated handle 5, one end portion 6 of which serves as a back for the brush 7. The brush is preferably formed of an odd number of rows of bristles, five such rows being illustrated on the drawing. Of these rows, the outermost rows 8 contain the longest bristles, the middle row 9 containing the shortest. Between these rows there may be provided a pair of intermediate rows 10, the tufts of the rows 10 being staggered with respect to the rows 8 and 9 to avoid undue weakening of the brush back 6.

For the proper cleansing of the enamel surfaces of the teeth and the proper massaging of the gum tissue it is desirable that the ends of the bristles rather than their sides be in contact with these surfaces. To this end the brush should be of sufficient width to embrace the teeth and jaw without spreading the outer rows of bristles to such an extent as to cause the sides of the bristles to wipe along the surfaces of the teeth and gums. For average sized teeth, the width of the brush at the base of the bristles should be approximately $\frac{3}{8}$ ", the bristles naturally spreading toward their free ends to an overall brush width of slightly over $\frac{1}{2}$ ". When viewed from the side, as shown in Figure 2, the ends of the bristles present, preferably, an arcuate contour, the longest bristles being at or near the center of the brush, as at 11, the length of the bristles becoming less and less toward the ends 12, 12. For the average mouth, the longest bristles at 11 may be approximately $\frac{9}{16}$ " in length, this length decreasing in both directions to a length of $\frac{3}{8}$ " at the ends 12. The length of the brush itself may conveniently be $1\frac{3}{8}$ ". As shown in Figure 3, the length of the bristles also varies in

a transverse direction so as to form a central channel extending from one end of the brush to the other. This channel may have an approximate U or V cross sectional shape, as shown. The bottom of the channel is defined by the central row 9 of bristles, these bristles being preferably about $\frac{1}{16}$ " in length. From the central bristles in the row 9 the bristles in the rows 10 and 8 progressively increase in length until the maximum length is reached at 11, this length, as hereinbefore stated, being preferably about $\frac{9}{16}$ ". Thus the maximum depth of the channel at the central point of the brush is about $\frac{3}{8}$ ". This depth, especially when increased by a yielding of the bristles in the row 9 when pressed against the tops of the teeth, is sufficient to receive and embrace teeth of average size, the longest bristles at or near the point 11 extending beyond the teeth to rest their ends against adjacent gum tissue.

While the bristle lengths herein given are suitable for adult teeth of average size, it is obvious that the length and proportions may be somewhat modified to receive and operate upon teeth of sizes other than average. The long bristles at 11 are, by reason of their length, more limber and yielding than the shorter bristles in the rows 9 and 10 so that the hard enamel surfaces of the teeth receive a treatment which is more vigorous than the comparatively gentle and yielding engagement of the long bristles with the gum tissue. Thus the surfaces of the teeth, and in particular the occlusal surfaces of the molars which contain natural fissures are subjected to a thorough cleansing action, while the gums are at the same time gently massaged. If desired, I may increase the difference in action between the central short bristles and the outer rows of long bristles by forming the outer rows with bristles of softer material than that of the bristles in the central row, but for ordinary purposes, the difference in stiffness between the outer and the central rows arising from the difference in length of the bristles, will be sufficient for my purposes as described.

It is important that the brush be adapted to cleanse thoroughly the teeth in the forward or curved portions of the jaws, as well as the molars. In order to provide for the proper conforming of the brush to these portions of the jaws, the length of the bristles in the outside rows 8 are decreased from the maximum point 11 to the ends 12, as hereinbefore described. The shortening of the bristles toward the ends of the rows 8 permits the brush to adapt itself to the teeth on the curved portions of the jaws so as to present bristle ends to all portions of these teeth. Thus, it is only necessary for the user to reciprocate the brush in its natural position on any portion of either jaw, the result being that the inner, outer, and the top surfaces

of the teeth and the adjacent portions of the gums, are simultaneously treated. This not only insures complete and thorough cleansing of the teeth and massaging of the gums, but also results in a considerable saving of time and effort in cleansing the teeth, since it is not necessary to rub the brush successively on the inner, outer and top surfaces of the teeth in three different operations, as is customary with an ordinary brush.

It is obvious that various modifications and changes in size and proportions from the specific description hereinbefore given can be made without departing from the spirit and scope of the invention as defined by the following claims.

I claim:

1. A tooth brush comprising a plurality of rows of bristles, the bristles in the central row being relatively short and of substantially uniform length from one end of the row to the other, the bristles in the outer rows being varied in length from a maximum near the middle of the brush to minima at its ends, presenting arcuate contours on the side faces of the brush to facilitate rocking of the brush around the inner arcuate surface of the row of teeth in each jaw, the arrangement and trim of the bristles being such as to provide simultaneous end-bristle contact with the grinding and side surfaces of one or more teeth and portions of the gum surfaces adjacent thereto.

2. A tooth-brush comprising a plurality of longitudinal rows of bristles, including a central row of relative short bristles and outer rows of longer bristles varying in length from minima at both ends of each outer row to a maximum at the middle of the row whereby a central longitudinal channel is formed with substantial depth from one of the brush to the other, and the side faces of the brush present an arcuate contour to facilitate rocking the brush around the inner arcuate surface of the row of teeth in each jaw.

In testimony whereof I have affixed my signature.

HARRY W. HICKS.
